UNITED STATES PATENT OFFICE.

CLARENCE P. FLORA, OF SOUTH BEND, INDIANA, ASSIGNOR, BY DIRECT AND MESNE ASSIGNMENTS, OF ONE-THIRD TO RICHARD G. INWOOD, ONE-THIRD TO SAMUEL M. ROBINSON, AND ONE-THIRD TO SAMUEL WHITEHALL, ALL OF SOUTH BEND, INDIANA.

METAL-BOUND BOX.

No. 918,839.

Specification of Letters Patent. Patented April 20, 1909.

Application filed May 21, 1908. Serial No. 434,136.

To all whom it may concern:

Be it known that I, CLARENCE P. FLORA, a citizen of the United States, residing at South Bend, in the county of St. Joseph and 5 State of Indiana, have invented certain new and useful Improvements in Metal-Bound Boxes, of which the following is a specification.

This invention relates to metal bound 10 boxes.

In the construction of metal bound boxes it is essential that the expense of manufacture be considered and that the box be composed of light and inexpensive material, 15 such as veneer or fiber board, because the boxes are transported numerous times from one place to another. In this character of box it is customary to bind the sides together and sometimes the ends also with 20 wire, twisting the ends of the wire together, and these twisted ends generally form projections which frequently injure the clothing and hands of those whose duty it is to handle the box.

25 It is one object of my invention to provide a light durable, inexpensive and efficient box whose parts when assembled are bound together by sheet metal and wire, the wire reinforcing the metal, and the parts, including 30 the binding elements, being so arranged and associated together, as to provide for neatness in appearance of the box, and particularly to provide against the possibility of injury to the person or clothing of those who 35 handle the box in the movement or transportation thereof from one place to another.

With the above and other objects in view, the present invention consists in the combination and arrangement of parts hereinafter 40 more fully described, illustrated in the accompanying drawings and particularly pointed out in the appended claims, it being understood that changes may be made in the form, proportion, size and minor details 45 without departing from the spirit or sacrificing any of the advantages of the invention.

In the drawings:—Figure 1 is a perspective view of a box constructed in accordance with my invention in condition for transportation. Fig. 2 is a similar view illustrating 50 the invention prior to the securing of the lid

in locked position. Fig. 3 is a detailed view of one corner of the box illustrating my improved means for securing the sides and ends together. Fig. 4 is a detail perspective view 55 of the metal binding strip with the reinforcement associated therewith. Fig. 5 is a detailed view of a corner of a box illustrating a modified form of invention.

Referring now more particularly to the 60 accompanying drawings, the reference characters 1 and 2 indicate the ends of the box, 3, 4, 5, and 6 indicating the sides of the box, and for the purpose of illustration, the side 3 constituting the bottom and the side 6 the 65 top or lid of the box. The sides and ends of the box are preferably held together by a metal sheet or strip 7 which is bent intermediate its edges and folded back upon itself with the free edge 8 of the under part 70 terminating short of the free edge 9 of the outer part, the free edge 9 being preferably bent back, as indicated, in alinement with the under part. This doubling of the metal strip strengthens it, and at the point where 75 it is bent back upon itself or at its bight portion 10, it receives between its inner and outer parts the binding wire 11 which latter, owing to its disposition between the inner and outer parts of the folded metal strip is 80 concealed from view, except at its free ends 12, for a purpose presently explained. After the metal strip has thus been formed and reinforced it is riveted or otherwise secured by suitable elements 13 to the sides of the box 85 and to the ends of the box by suitable elements 14. The binding strips are preferably secured to the sides of the box, in their flat condition prior to assembling the sides with the ends of the box, and in order that the 90 sides may be caused to assume their right angular relation with one another for engagement with the corresponding ends of the sides of the box, I miter the middle strips equidistant points throughout their length, 95 as indicated at 15 in Fig. 4, so that as the sides assume their right angle relation to one another, resulting in a consequent bending of the strips and the reinforcing elements of the latter, the corresponding adjacent mitered edges of the different sides may be 100 thrown into abutting relation, as particu-

larly illustrated in Figs. 1 and 2. When the sides have been thus assembled, the ends 1 and 2 are placed in position at the respective ends of the sides and within the metallic binding strips when the latter are secured to the outer faces of the ends. The metallic strips may be secured to the sides and ends by suitable rivets 16 and 17 respectively, or in any other suitable manner.

10 The side 6, which forms the lid of the box, has that part of the metallic binding strips secured thereto not fastened to the ends 1 and 2 until it is desired to ship the box, said side or lid 6 being shown in open position in Fig. 2. When the box is ready for shipment the side or lid 6 is brought down to closed relation with the sides and ends when the free opposite ends of the binding and reinforcing wire 11 will be brought into juxtaposition and when the binding wires and reinforcements 11 may be twisted together, as indicated at 18 in Fig. 1, securing all the sides firmly and rigidly together, and by virtue of suitable fastenings 19 passed through that part of the metal strip which over-laps the outer faces of the ends 1 and 2, the parts of the box may be further secured together against displacement, as will be obvious. However, these fastenings 19 may be eliminated from the structure altogether, if desired, so that by merely untwisting the opposite ends 12 of the binding and reinforcing wires 11 the lid part 6 of the box may be quickly opened to permit of access to the box. Of course, it is immaterial which side of the box forms the lid part.

From the foregoing, it will be seen that I provide for a triple reinforcement of the box, in that I double the metallic binding strip 40 and further reinforce the double binding strip with the wires 11. It will also be seen that by virtue of placing the binding and reinforcing wires 11 within the double binding strip that the binding and reinforcing wires 45 11 are concealed completely from view except at one point, and that is where they are twisted together. It is intended that the free ends 12 of the binding and reinforcing wires 11 be twisted together in such a manner as to obviate projecting ends, in which event, in view of the concealment of the remaining portions of the wires, there is little, if any, likelihood of persons handling the box to become injured by projections or have 55 their clothing torn incident to projections. It will also be apparent that the box is simple and inexpensive of manufacture and that the use of separate hinges is obviated incident to the metallic strips forming not only 60 strengthening and fastening elements but also performing the function of hinges.

In Fig. 5 wherein there is shown one side 20 and end 21, the metallic reinforcing strip 22 is formed similar to the metallic reinforce-

ing strip hereinbefore described, and it will 65 also be seen that it is provided with a binding and reinforcing wire 23. The material difference between this modified form of strip and that first described resides in the spacing of the inner and outer parts of the strip to 70 provide a space for the slidable reception of the ends 21, by virtue of which, separate fastenings are not needed to secure the ends in place. In this modified type of box it may be readily knocked down or folded by the 75 consumer. The box sides would be folded and the ends inserted in the spaces between the inner and outer parts of the strip, and the reinforcing wires when twisted, would thus lock the ends against displacement without 80 any securing means whatever.

It will be added in conclusion that the metal strips not only support the box parts in their assembled relation, but they also surround the box with the reinforcing wires, 85 which latter, as heretofore stated, are held against displacement by the strips. In frequent uses the hinge points of the metal strip break, and the reinforcing wires thus assume the function of a hinge and hold the 90 lid in proper relation with the box, although, of course, prior to the breaking of the metallic strips, if breakage should occur, the strips themselves coöperate with the wires in performing the hinge connection of the lid. 95

What is claimed is:—

1. In a metal bound box, the sides and the ends of the box, sheet metal strips each bent back upon itself to provide a bight portion along one edge, one free edge of the folded strips extending beyond the other free edge thereof and again bent back upon itself into alinement with said other edge, the metal of each strip thus folded being again bent back upon itself to provide two angle portions, one 100 portion for engagement with one side of the box and the other angular portion arranged for engagement with one end of the box, and a binding wire fitted between said bent back portions of the strips and disposed in said 105 bight portions.

2. In a metal bound box, the sides and the ends of the box, sheet metal strips each bent back upon itself to provide a bight portion along one edge, a binding wire fitted in the 110 bight portion of each strip, one free edge of the folded strips extending beyond the other free edge thereof and again bent back upon itself into alinement with said other edge, the material of each strip thus folded being again 115 bent back upon itself to provide two portions arranged at an angle to each other, the angular portions having the binding wires therein being disposed upon the sides of the box and the other angular portion being disposed against the ends of the box. 120

3. A metal bound box comprising sides and ends, and metal strips each bent back

upon itself to provide a single bight portion along one edge, each of said strips being again bent longitudinally to dispose one folded edge of each strip at an angle to the 5 opposite edge of each folded strip, one angle portion being disposed against one side of the box and the opposite angle portion being disposed against the corresponding end of the

box, and a binding wire fitted in each bight portion.

In testimony whereof I affix my signature, 10 in presence of two witnesses.
